[57] CLAIM

The ornamental design for a truck-mounted van body
for wireline deployment and retrieval apparatus, as
shown and described.

DESCRIPTION

FIG. 1 is a top right rear perspective view of a truck-
mounted van body for wireline deployment and re-
trieval apparatus showing our new design, it being un-
derstood that the broken lines are for illustrative pur-
poses only and form no part of the design claimed;
FIG. 2 is an enlarged front elevation view thereof;
FIG. 3 is an enlarged right side elevation view thereof;
FIG. 4 is an enlarged rear perspective view thereof;
FIG. 5 is an enlarged left side elevation view thereof;
FIG. 6 is an enlarged top perspective view thereof; and
FIG. 7 a perspective view similar to that of FIG. 1, with
the rear doors and roof panel being shown in open
condition.
